UNITED STATES PATENT OFFICE.

ROLLIN M. HYDE, OF DETROIT, MICHIGAN, ASSIGNOR TO MCCORD RADIATOR & MFG. CO., OF DETROIT, MICHIGAN, A CORPORATION OF MAINE.

CONDENSER FOR REFRIGERATING MACHINES.

Application filed December 13, 1926. Serial No. 154,379.

This invention relates to improvements in condensers for use in connection with refrigerating machines, such as are installed in houses, apartments, hotels, and the like.

5 In my copending application, Serial No. 141,491, filed October 14, 1926, I have shown, described, and claimed a condenser generally circular or annular in form and adapted to be located directly in front of 10 the air circulating fan of the compressor assembly so that substantially all portions of the condenser are in the direct path of the air currents produced by the fan to be effectively cooled thereby.

15 The main object of my present invention is to provide a condenser of this general type but constructed to receive the fan within the center of the condenser and thus completely surround the fan so as to be effectively cooled by the air currents sent off 20 radially from the fan or other air circulating device which may be used.

By having the condenser surround the fan or other air circulating device and receiving 25 the air currents radially therefrom, the condenser to be most effective need not be limited in size to the outer diameter of the fan, as in my copending application as aforesaid, but may be made considerably larger 30 and thus have a greater capacity for refrigerant circulation therethrough without unduly increasing the size of the entire condenser assembly.

35 Moreover, in having the condenser surround the fan, the condenser forms a housing for the fan and avoids the use of separate casings or shields for protective and safety purposes, as when fans with exposed fan blades are used.

40 The invention consists further in the matters hereinafter described and claimed.

In the accompanying drawings—

Fig. 1 is a front elevational view of a condenser constructed in accordance with my 45 invention and shown surrounding an air circulating fan;

Fig. 2 is a side elevational view of the condenser and fan assembly as illustrated in Fig. 1; and

50 Fig. 3 is an enlarged vertical sectional view taken on the indirect line 3—3 of Fig. 2 to show the manner in which the tubes are connected with a header of the condenser.

The condenser of my invention consists 55 of a multiplicity of curved tubes 1, 1 ar-

ranged in circular form and connected for the circulation of a refrigerant therethrough by hollow headers 2, 2, as shown in Fig. 1. The tubes 1, 1 are arranged in side by side relation and the headers 2, 2 are disposed 60 transverse thereto, so as to provide with the tubes a hollow structure to receive within the same an air circulating fan 3 or other device for blowing air over the condenser, as shown in Figs. 1 and 2. The shaft 4 of the 65 fan extends outward from the center of the condenser assembly and may be rotated or driven in any suitable manner from the electric or other motor of the compressor unit. It is general practice to mount the 70 fan directly on the shaft of the motor, as this gives greater speed to the fan, and as the fans are usually small in diameter, a high speed is very beneficial.

The fan 3 when of the bladed type, as illustrated in said figures, has its blades set at such a pitch that they discharge air currents radially therefrom and thus blow air over the condenser assembly which surrounds the same. Thus the condenser is positioned 80 to have substantially, if not all of its radiating surface (including that of the tubes and the headers) within the area of the fan's influence and be effectively cooled thereby without limiting the size of the condenser 85 to the outer diameter of the fan, as in my copending application as aforesaid. Moreover, with this arrangement, the fan need not be unduly large and bulky, as the condenser in surrounding the fan may be 90 brought close about the outer periphery thereof. This enables me to provide a condenser of the desired radiating surface in a very limited space without interfering with the close arrangement of the other parts 95 making up the compressor unit. Making the condenser in circular or annular form gives it a neat and pleasing appearance fitting in well with the feature of compactness required for compressor units as used for 100 refrigerating machines. Furthermore, the condenser houses the fan 3, and thus in itself provides a protective shield or guard about the exposed blades.

The particular structure shown in Figs. 1 105 and 2 has a pair of headers 2, 2 diametrically disposed and connected on opposite sides by a series of semicircular tubes 1, 1. Each tube carries a heat radiating fin strip 5, which may be spirally wound about the out- 110

side thereof and extending from one header to the other. Of course, tubes without fins may be used if desired, or a combination of plain and finned tubes may be used, as required.

Moreover, in Figs. 1 and 2, I have shown the condenser with the headers 2, 2 arranged at an inclination to the axis of rotation of the fan 3 and with the semicircular tubes 1, 10 1 on one side of the headers in the same planes as the corresponding tubes on the opposite side of the headers. The tubes are connected with their respective headers along the longitudinal center lines of the latter, 15 and this makes the several sets of tubes have different diameters, with the latter increasing from one end of the headers to the other. When the headers are disposed to incline back over the fan, as shown in Fig. 2, the tubes at the outer ends of the headers are of the smallest diameter, while the tubes at the inner ends of the headers have the largest diameter. This gives greater compactness to the condenser assembly.

20 25 The headers 2, 2 are preferably stamped from sheet metal and are made alike. Each header is made in two half sections having marginal flanges 6, 7, by means of which they are secured together by lock-seaming, soldering, stitch-welding, or any other preferred method. In the drawings, I have shown the flanges connected together by lock-seaming, which is accomplished by making one flange wider than the other so that the wider flange may be turned over and pressed against the narrower flange and soldered, to provide a leak proof joint.

30 35 The tubes 1, 1 are connected with their respective headers 2, 2 by having their ends entering flanged holes 8, 8, as detailed in Fig. 3. These holes are provided in the sheet metal body of the header sections, and the tubes are made tight in the holes by soldering, flanging or some other method. 40 45 To connect the condenser in the refrigerant circulation, one header is provided with an inlet pipe and the other with an outlet pipe, these pipes being indicated by 9, 10, respectively, in Figs. 1 and 2.

In making the headers of sheet metal and 50 in sections, building of the condenser is greatly facilitated, for the reason that the two sets of semicircular tubes 1, 1 may be connected with the respective half sections 55 of the headers before the latter are joined together to complete the headers. The tubes 1, 1 are preferably seamless so as to reduce the number of joints in the assembly. This lessens the number of joints and possibility 60 of leaks, yet allowing the condenser to be made relatively light but strong and rigid in construction. In use the condenser receives refrigerant under a high pressure and a high temperature and discharges the refrigerant at substantially the same pressure 65 but at a considerably lower temperature due to the cooling action of the condenser. The headers and tubes have relatively thin metal walls for the rapid cooling of the refrigerant.

70 The details of structure may be variously changed and modified without departing from the spirit and scope of my invention.

I claim as my invention:

1. A condenser for refrigerating machines, 75 consisting of opposed converging headers having inlet and outlet openings, and a multiplicity of tubes on opposite sides of the headers and connected therewith for the circulation of a refrigerant therethrough, said 80 tubes being curved and arranged in side by side relation and connected with the headers in a manner to form circles increasing in diameter from one end of the headers to the other.

2. In a condenser assembly for refrigerating machines, the combination with a rotary air circulating fan, of a condenser for the circulation of a refrigerant therethrough and surrounding the outer periphery of the fan 90 for receiving air therefrom, said condenser having a multiplicity of curved tubes arranged in side by side relation to form circles increasing in diameter from the front of the fan.

95 In testimony whereof I affix my signature this 10th day of December 1926.

ROLLIN M. HYDE.
